UNITED STATES PATENT OFFICE.

VEIT A. HAIN, OF CHICAGO, ILLINOIS, ASSIGNOR TO GENERAL ELECTRIC COMPANY, A CORPORATION OF NEW YORK.

SUBSTATION APPARATUS.

1,315,830.

Specification of Letters Patent.

Patented Sept. 9, 1919.

Application filed June 23, 1916. Serial No. 105,506.

To all whom it may concern:

Be it known that I, VEIT A. HAIN, a citizen of the United States, residing at Chicago, in the county of Cook, State of Illinois, have invented certain new and useful Improvements in Substation Apparatus, of which the following is a specification.

My invention relates to sub-station apparatus, and more particularly to an arrangement for the protection of rotary transformers which are interposed between two systems, whereby, at the same time, the greatest possible continuity of service will be maintained.

15   Rotary transformers as used in sub-stations are subject to severe overloads, especially when used in railroad service. Adequate protection can be secured by the use of overload circuit breakers but if these 20 must be manually reset, the service is interrupted for a greater or less period. The problem then is to provide some arrangement which shall protect the apparatus, and at the same time maintain the continuity 25 of service to as high a degree as possible. The arrangement which I shall herein propose is adapted for use with any rotary transformer connecting two systems, but it is especially adapted, because of its automatic operation, to use in remote control sub-stations or in sub-stations which are entirely automatic.

30   My invention consists in an arrangement for protecting a rotary transformer upon the occurrence of overloads which shall at the same time put said transformer in service again within as short a space of time as possible, and which shall become ineffective after having operated for a predetermined number of times at predetermined intervals.

35   My invention will be more readily understood from the following specification taken in connection with the accompanying drawing, in which Figure 1 is a diagram showing my invention applied to a remote-control sub-station; Fig. 2 is a diagrammatic view showing the detailed construction of one of the relays used.

40   45   Although I have herein illustrated my invention as applied to a remote-control sub-station in which the rotary transformer is started by an operation at the main generating station, it will be understood that 50 it is equally applicable to a sub-station which

is entirely automatic or to a manually-controlled sub-station.

In the arrangement shown the apparatus which is located at the main generating station, is inclosed within a dotted square at 55 the lower lefthand corner of the sheet. An alternating current generator 10, supplies current to a supply system 11. This supply system is adapted to be connected to feeders 12 through a switch 13, a starting transformer 14, and a voltage regulator 15 preferably of the induction type. The remaining apparatus by means of which power is supplied to the direct current distribution system 16, is located at a sub-station which 60 may be at any desired distance from the generating station.

The sub-station will be seen to include a rotary transformer 20, here shown as a rotary converter, which is adapted to be connected to the low voltage and full voltage taps respectively, of the starting compensator 23. The latter is supplied with alternating current from the feeders 12 through the line switch 24. It will be seen that the 65 switches 21 and 22 are mechanically connected by means of a pivoted bar 25 so that they are interlocked and further so that the switches will remain in the position to which they are moved by the energization of one 70 or the other of their coils. This is, however, only intended as a diagrammatic representation of any construction adapted to operate in the desired manner. The direct current terminals of the rotary transformer 75 are adapted to be connected to the distribution system 16 by means of a circuit breaker 20. This circuit breaker may be of any suitable type, and will be seen to comprise a closing coil 31, a trip coil 32, and an interlock switch 33. The energization of the 80 closing coil is controlled by the contacts of a differential voltmeter 35, having one coil responsive to the voltage of the distribution system, as determined by other sub-stations 85 or generating stations, not shown, and the other coil responsive to the terminal voltage of the rotary transformer. When the voltage of the rotary transformer is slightly 90 greater than that of the distribution system, the contacts of this voltmeter will be closed and cause the energization of coil 31, provided the circuit breaker is in its open 95 position so that the switch 33 will complete the energizing circuit.

An overload relay 40 has been provided which is responsive to the power transferred between the supply system and the distribution system, and has the two switch members 41 and 42. Switch 42 is arranged to complete an energizing circuit for the tripping coil 32 when the circuit breaker is in its closed position. The tripping coil is also arranged to be energized from either a centrifugal speed limiting switch 53 or from a reverse current relay 36. The energizing circuit for the instantaneous relays 43 and 44 is completed through the switch 41 on the overload relay. The first of these relays is in normally closed position when deenergized, and energizes the time limit relays 45 and 46 of special construction, as shown in Fig. 2. Relay 44 is adapted to energize the starting contactor 21 while the time limit relay 45 is adapted to energize the running contactor 22.

The construction of the time limit relays 45 and 46, one conception of which is diagrammatically shown in Fig. 2, is such that they may be closed for a predetermined number of times at predetermined intervals, and then become ineffective. To this end, each of these relays may have one of its contacts 60 mounted upon a movable member 61 which is mechanically connected to the core 62 of the closing solenoid. Mounted upon the movable member 61 is a spring pressed pawl 63, engaging a ratchet 64 provided with a stop pin 65. At each closure of the contacts, the pawl 63 will move the ratchet wheel 64 forward for one notch until it has been actuated for a number of times determined by the design of the ratchet wheel 64 and the location of the stop pin 65. After this number of closing movements has taken place, the stop pin 65 will engage some fixed member, such as the support 66, to prevent further closure of the switch. The time interval between the energization of the coil and the closure of the switch is determined by any suitable device, such as the dash-pot 67, by means of which the closing movement may be retarded for any suitable interval of time.

The rotary transformer is provided with an exciting winding 50 whose circuit is controlled by means of a field contactor 51 and a centrifugal speed responsive switch 53'. When the rotary transformer has attained the desired speed, which will preferably be slightly less than synchronous speed, the switch 53' will energize the field contactor 51 and connect the exciting winding 50 between the positive and negative sides of the distribution circuit 16 through the winding of the protective relay 58, the resistances 54 and 55, and the winding of the protective relay 59. As is customary in railway work, the negative side of the distribution circuit is grounded, as has been indicated

in Fig. 1. The winding of the contactor 51 is protected from overheating by means of a resistance 52 which is short circuited in the open position of the contactor. In parallel with this winding is the winding of the time limit relay 56, whose contacts control the energization of a contactor 57 whose contacts are arranged in series with those of the relay 46 to short circuit the resistance 55.

Assuming that the distribution circuit 16 is energized from some other source of supply, and that the generator 10 is supplying current to the supply system 11, the rotary transformer may be set in operation and connected between the supply system and the distribution system by the operator at the main generating station. It will be assumed that the line switch 24 is in its closed position, and that the running contactor 22 is closed, being energized through the contacts of the relay 45 which in turn is energized through the relay 43. The operator will then move the voltage regulator to its maximum buck position and the switch 13 to its left hand position. The starting transformer 14 will supply a reduced voltage to the rotary 20, which will be still further reduced by means of the voltage regulator 15. The rotary will then start and will gradually increase in speed until it reaches synchronism. When the speed is slightly below synchronism, the speed responsive switch 53' will energize the field contactor 51 and connect the exciting winding 50 to the distribution circuit with all of the resistances 54 and 55 in circuit. This exciting winding is preferably connected to the distribution circuit instead of directly to the terminals of the rotary transformer to insure that the voltage shall build up in the right direction. The operator will then move the switch 13 to its right hand position so as to supply the full voltage of the system 11 to the feeders 12, less the reduction in the regulator 15. About this time the relay 56 which has been retarded by its time limiting dash-pot, will close and energize the contactor 57 so as to short circuit the resistance 55, thereby supplying full field current to the rotary transformer. The operator will then set the voltage regulator 15 in its running position so that the A. C. voltage supplied to the rotary transformer will be slightly increased. When the direct current voltage has reached a value slightly in excess of the voltage of the distribution circuit, the differential voltmeter 35 will energize the closing coil 31 of the circuit breaker 30, and connect the rotary transformer to the distribution circuit. The particular method of starting the rotary transformer and putting the same in operation is, however, not an essential part of my invention. Similarly, the provision of a reverse current relay arranged to disconnect the transformer from the distribution cir-

cuit in case of a failure of the alternating current voltage, and consequently a reversal of power, as well as the speed limiting switch 53, which is set to close at a higher speed than the switch 53', and the field protecting relays 58 and 59, are old and well-known.

I have, however, provided an arrangement whereby, upon the occurrence of an overload, the transformer will be automatically disconnected from the distribution circuit, the supply voltage decreased, the excitation decreased, these conditions restored after a predetermined interval, and the transformer then reconnected to the distribution circuit. This action will be repeated not more than a predetermined number of times, say for example five times, so that in case the short circuit or other cause of overload upon the distribution circuit 20 shall have cleared itself in the meantime, the transformer may be connected to the distribution circuit and the continuity of the service assured with a minimum delay. If the cause of overload has not been removed at this time, my arrangement must be normally restored to its original condition before further operation can be had when the trouble is cleared. It will be found that for this purpose, my invention 30 is equally applicable to a manually controlled substation or to a remote controlled or an automatic sub-station. As has already been pointed out, the occurrence of an overload would cause the energization of the trip coil 32 to open the circuit breaker and at the same time will energize the relays 43 and 44. The energization of the relay 43 will deenergize the relays 45 and 46 which will immediately open allowing the starting contactor 21 to be closed by means of the relay 44, and the resistance 55 to be inserted in circuit with the exciting winding and thereby reduce the direct current voltage. As soon as the circuit breaker has 45 opened, the overload relay will open and again deenergize the relays 43 and 44. The starting contactor 21 will, however, remain in its closed position. After an interval, of say ten seconds, relay 45 will be again closed and will energize the running contactor 22 to increase the voltage supplied to the rotary transformer. After an interval, of say fifteen seconds, or five seconds after the closing of the relay 45, the relay 55 46 will be closed to short circuit the resistance 55. As soon as the direct current voltage has reached a value slightly in excess of the voltage of the distribution circuit, the differential voltmeter 35 will cause the circuit breaker 30 to again close and if the cause of the trouble has not been removed, the overload relay 40 will again come into action and cause a repetition of the cycle which has been described. This will be 60 continued at regular intervals and if the

cause of the trouble has not been removed after a certain number of attempts to keep the transformer in service, then the construction of the relays 45 and 46 is such that they will become ineffective and prevent further operation until they have been manually reset.

I have herein described one particular embodiment of my invention whereby the objects set forth may be attained, but it will be understood that although I have shown my invention as applied to a particular type of substation and as carried out with a particular arrangement of apparatus, it is equally applicable to any arrangement of 80 a rotary transformer connecting a supply system and a distribution system. It will be further understood that various changes and modifications will occur to those skilled in the art. I do not wish, therefore, to be 85 limited to the exact arrangement shown, but seek to cover in the appended claims all those modifications which come within the true scope and spirit of my invention.

What I claim as new and desire to secure 90 by Letters Patent of the United States, is:

1. In combination, a supply system, a distribution system, a rotary transformer interposed between said systems, and means operable in response to electrical conditions 95 of said transformer for effecting the connection and disconnection of said transformer and one of said systems and for first decreasing and then increasing the voltage applied to said transformer, said means being capable of automatic operation to increase said voltage only a predetermined number of consecutive times.

2. In combination, a supply system, a distribution system, a rotary transformer interposed between said systems, means operable in response to the power transferred by said transformer for effecting the disconnection of said transformer and distribution system and for first decreasing and 105 then increasing the voltage applied to said transformer by said supply system, said means being capable of automatic operation to increase said voltage only a predetermined number of consecutive times, and 110 means responsive to the ratio of the voltages of said transformer and distribution system for reconnecting the same.

3. In combination, a supply system, a distribution system, a rotary transformer interposed between said systems, means operable 120 in response to the power transferred by said transformer for effecting the disconnection of said transformer and distribution system and for first decreasing and after a predetermined interval increasing the voltage applied to said transformer by said supply system, said means being capable of automatic operation to increase said voltage only 125 a predetermined number of consecutive 130

times, and means responsive to the ratio of the voltages of said transformer and distribution system for reconnecting the same.

4. In combination, a supply system, a distribution system, a rotary transformer interposed between said systems, and means operable in response to electrical conditions of said transformer for effecting the connection and disconnection of said transformer and one of said systems and for first decreasing and then increasing the excitation of said transformer, said means being capable of automatic operation to increase said excitation only a predetermined number of consecutive times.

5. In combination, a supply system, a distribution system, a rotary transformer interposed between said systems, means operable in response to the power transferred by said transformer for effecting the disconnection of said transformer and distribution system and for first decreasing and then increasing the excitation of said transformer, said means being capable of automatic operation to increase said excitation only a predetermined number of consecutive times, and means responsive to the ratio of the voltages of said transformer and distribution system for reconnecting the same.

6. In combination, a supply system, a distribution system, a rotary transformer interposed between said systems, means operable in response to the power transferred by said transformer for effecting the disconnection of said transformer and distribution system and for first decreasing and after a predetermined interval increasing the excitation of said transformer, said means being capable of automatic operation to increase said excitation only a predetermined number of consecutive times, and means responsive to the ratio of the voltages of said transformer and distribution system for reconnecting the same.

7. In combination, a supply system, a distribution system, a rotary transformer interposed between said systems, and means operable in response to electrical conditions of said transformer for effecting the connection and disconnection of said transformer and one of said systems and first de-

creasing the voltage applied to and the excitation of said transformer and then increasing the voltage applied to and the excitation of said transformer, said means being capable of automatic operation to increase the voltage applied to and the excitation of said transformer only a predetermined number of consecutive times.

8. In combination, a supply system, a distribution system, a rotary transformer interposed between said systems, means operable in response to the power transferred by said transformer for effecting the disconnection of said transformer and distribution system and for first decreasing the voltage applied by said supply system to and the excitation of said transformer and after a predetermined interval increasing the voltage applied by said supply system to and the excitation of said transformer, said means being capable of automatic operation to increase the voltage applied to and the excitation of said transformer only a predetermined number of consecutive times, and means responsive to the ratio of the voltages of said transformer and distribution system for reconnecting the same.

9. In combination, a supply system, a distribution system, a rotary transformer interposed between said systems, means operable in response to the power transferred by said transformer for effecting the disconnection of said transformer and distribution system and for first decreasing the voltage applied by said supply system to and the excitation of said transformer and after a predetermined interval increasing the voltage applied by said supply system to said transformer and subsequently increasing the excitation of said transformer, said means being capable of automatic operation to increase the voltage applied to and the excitation of said transformer only a predetermined number of consecutive times, and means responsive to the ratio of the voltages of said transformer and the distribution system for reconnecting the same.

In witness whereof, I have hereunto set my hand this 17th day of June, 1916. 100

VEIT A. HAIN.
